ELIJAH ROBERTSON HILL, OF NEW ALBANY, MISSISSIPPI.

CLOSET-TANK BALL-COCK.

1,212,056.

Specification of Letters Patent.

Patented Jan. 9, 1917.

Application filed January 5, 1916. Serial No. 70,399.

To all whom it may concern:

Be it known that I, ELIJAH R. HILL, a citizen of the United States, and a resident of New Albany, in the county of Union and

5 State of Mississippi, have invented a new and Improved Closet-Tank Ball-Cock, of which the following is a full, clear, and exact description.

This invention relates to plumbing appliances and has particular reference to ball cocks for flush tanks.

Among the objects of the invention is to provide a new and specific form of valve mechanism including a flexible diaphragm 15 located between relatively fixed and movable valve parts, said movable part being controlled by lever mechanism from the float.

A further object of the invention is to improve the construction of the body portion 20 of the valve with respect to the means for locking the diaphragm in operative position.

A still further object of the invention is to adapt the improved valve mechanism to either low-down or high tanks.

25 With the foregoing and other objects in view, the invention consists in the arrangement and combination of parts hereinafter described and claimed, and while the invention is not restricted to the exact details of 30 construction disclosed herein, still for the purpose of illustrating a practical embodiment thereof reference is had to the accompanying drawings, in which like reference characters designate the same parts in the 35 several views, and in which—

Figure 1 is a vertical sectional view of the main parts of one form of the invention; Fig. 2 is a horizontal sectional detail on the line 2—2 of Fig. 1; Fig. 3 is a vertical 40 sectional view of the same invention but embodying modifications; and Fig. 4 is a horizontal sectional detail on the line 4—4 of Fig. 3.

In the drawings I show at 10 a portion of 45 a flush tank in the bottom of which is fitted a spud 11 in any well known or approved manner. A valve stem 12 extends upwardly from the spud to any desired height, depending upon the character or location of 50 the tank, and terminates in or has secured upon it a valve head 13, the active end portion of which preferably consists of a thimble 14 of glass, porcelain or the like constituting the valve seat proper. Said head 13 55 is provided with an annular shoulder 15 surrounding and spaced from the valve

seat, and this portion of the device, as shown in Fig. 1, is tapped into the lower portion of the valve body 16. The body 16 is secured rigidly in position by any suitable means as through the valve head 13 and supply valve stem 12, and the water received through the stem and valve seat is adapted to be delivered through and from the body by various means. In Fig. 1 I 60 show a delivery spout 17 leading laterally from the axis of the body and thence bent downwardly, the water flowing from the spout through a hush tube 18 where it is delivered at the bottom of the tank. Obviously the length of this hush tube will be 65 proportioned according to the height of the valve mechanism above the bottom of the tank.

The upper portion of the body 16 is 70 formed with a rabbet 19 constituting a fixed seat for the periphery of a flexible diaphragm 20 spanning the valve seat. A crown or ring 21, shown as of annular or hollow cylindrical form, is located between 75 the shoulder 15 of the head and the periphery of the diaphragm, and thereby, when the head is screwed tightly into the body, the diaphragm is locked rigidly and permanently in place. The crown 21 is provided with a plurality of lateral openings 80 85 22 through which the water may pass laterally through the crown.

At 23 is indicated a plunger fitted slidably in the upper portion of the body in axial alignment with the valve seat 14 and valve stem and adapted to bear downwardly upon the central portion of the diaphragm to constitute a closure for the supply pipe. The water pressure acting through the supply pipe will lift the diaphragm unless the plunger is held down by some external 90 means.

The plunger 23 is shown provided with a transverse slot 24 forming a bearing for a 100 lever 25 pivoted at 26 upon a rigid extension from the body 16. The float rod 27 has adjustable jointed connection at 28 with another lever 29 pivoted at 30 to another rigid extension 31. A link 32 connected to the respective levers 25 and 29 causes a movement 105 of the plunger 23 toward or from the valve seat according to whether the float (not shown, but connected to the rod 27 in the usual manner) rises or falls according to the 110 depth of the water in the tank. This downward movement of the plunger serves to

cause the flexible diaphragm 20 to engage the valve seat and stop the flow of water through the valve stem. With the delivery of the water from the tank in any approved manner not constituting any part of this invention, and the lowering of the float rod, the plunger will be lifted and thereby the water will pass upwardly through the valve stem and valve seat, thence outwardly through the openings 22 of the crown and through the spout 17 and hush tube 18 to refill the tank. A common form of refill tube 33 for the bowl may be connected to the valve body if desired, according to the type or elevation of the tank valve mechanism. By loosening the winged nut 34 at the joint 28, the float rod 27 may be adjusted up or down with respect to the lever 29, and thereby the action of the float will be varied to control the action of the plunger according to the amount of water desired to be supplied to the flush tank.

In Figs. 3 and 4 the construction embodies the same novel features with respect to the valve seat diaphragm and equivalent means associated therewith. The supply valve stem 12' is supported, as above described, upon a spud 11 and carries a head 13' at its upper end in which is supported in axial alignment with the valve stem a non-corrodible valve seat 14. The head 13' is tapped into the lower portion of the body 16' substantially as previously described, and such connection serves to cause the crown 21 to grip the periphery of the diaphragm 20 against the upper portion of the body in the rabbet 19. This crown also is provided with openings 22 communicating with a refill tube 33. The structure of the head 13', how-

ever, differs in this respect in that it consists of two parts arranged concentrically and rigidly connected to each other by means of webs 35, and the outer portion of the head includes a downwardly projecting flange 36 having an internal thread into which is connected a hush tube 18' surrounding the supply stem and delivering the water received from the supply stem and head close to the bottom of the tank 10 and around the base of the supply stem.

I claim:—

In flush tank valve mechanism, the combination of a supply pipe having a head and valve seat at its upper end, said head having a laterally projecting annular shoulder, a hollow rigid body into which said head and valve seat are projected and secured, said body having an annular shoulder directly above the head shoulder, a flexible diaphragm spanning the upper portion of the body cavity across the valve seat, and fitted against the body shoulder, a hollow cylindrical crown located between the head and the periphery of the diaphragm serving to clamp the diaphragm in place, said crown having one or more lateral radial openings, a member movable toward and from the valve seat and located upon the opposite side of the diaphragm therefrom, and float controlled devices connected to said movable member and determining its position with respect to the valve seat according to the depth of the water in the tank.

ELIJAH ROBERTSON HILL.
